US00D917434S

(12) **United States Design Patent** (10) **Patent No.:** **US D917,434 S**
Pfleiderer et al. (45) **Date of Patent:** **** Apr. 27, 2021**

(54) **DENTAL TOOL WITH TRANSPONDER**

(71) Applicant: **DENTSPLY SIRONA Inc.**, York, PA (US)

(72) Inventors: **Martin Pfleiderer**, Auvernier (CH); **Moritz Manderscheid**, Darmstadt (DE)

(73) Assignee: **DENTSPLY SIRONA INC.**, York, PA (US)

(**) Term: **15 Years**

(21) Appl. No.: **29/645,302**

(22) Filed: **Apr. 25, 2018**

(51) **LOC (13) Cl.** **14-03**

(52) **U.S. Cl.**

USPC **D14/230**

(58) **Field of Classification Search**

USPC D14/230, 232-236; D24/152

CPC .. H01Q 1/24; H01Q 1/22; H01Q 1/38; H01Q 9/28; H01Q 1/12
